THROAT FOR FASTENING INSERTING MACHINES

James A. Harkeem, Manchester, N. H., assignor to
United Shoe Machinery Corporation, Fleming-
ton, N. J., a corporation of New Jersey

Application November 30, 1945, Serial No. 631,880

5 Claims. (Cl. 1—5)

1

This invention relates to machines for inserting fastenings and is herein disclosed as embodied in a tack driving machine of the type illustrated in United States Letters Patent Nos. 1,106,393 and 1,312,598, granted on August 11, 1914, and August 12, 1919, respectively, on applications filed in the names of Fred L. MacKenzie and Frank H. Warren, respectively.

It is an object of the present invention to provide machines of the aforesaid type with improved means adapted to facilitate the use of such machines in securing steel shank pieces to shoe bottoms.

For the purpose in view, the construction and arrangement of the operating instrumentalities of the illustrated machine, which instrumentalities primarily comprise a work engaging throat through which the fastenings, such as tacks, are passed by a driver during the tack driving operation and tack holding jaws extending from the throat, is such that the jaws pivotally engage, by means of upwardly extending hook shaped portions, a beaded portion provided on the lower end of the throat. The jaws are held closed against each other so as to form a tack holding pocket and to act as work gages partly entering tack holes provided in the steel shank piece, by an annular spring surrounding the jaws and arranged to yield so as to permit the jaws to separate upon the driving of a tack and to move out of the tack hole in the steel shank piece after the point of the tack has entered the work. Preferably and as herein illustrated, means is provided for holding the above mentioned jaws with their hook shaped portions at all times in pivotal engagement with the beaded portion on the lower end of the throat.

As will be noted, the mechanism provided in accordance with this invention is of extremely simple construction and its parts may be easily replaced in case of wear and tear.

In the accompanying drawings,

Fig. 1 is an angular view of part of a tack driving machine in which the present invention is embodied;

Fig. 2 is an angular bottom view of the throat of the machine illustrated in Fig. 1;

Fig. 3 is a sectional view of the throat and work parts presented thereto;

Fig. 4 is a view similar to Fig. 3 with the machine parts assuming a different position in a cycle of operations.

As illustrated in the drawings, the present machine is provided with a throat 20 which, in substance, is a cylindrical member externally threaded on its upper portion and having a flange or collar. It is in threaded engagement with a tapped hole provided in the machine frame. The tacks are delivered to the throat by a separator 22 which serves to separate the lowermost tack

2

in a raceway 24 and to drop it into the throat passage which also serves to guide a driver 26 reciprocating therein to insert the tack into the work parts.

5 The work in the present instance is a partially processed shoe comprising a shoe upper U secured in lasted relation to an insole I mounted on the bottom of a last L, it being desired at this stage of the shoemaking operation to secure a steel shank piece S to the shoe bottom, as is the common practice. The steel shank piece, which is slightly curved in the direction of its longitudinal axis, is provided near its opposite ends with tack holes through which the tacks securing the shank piece to the shoe bottom are inserted. The tack driven through the hole provided in the heel-end portion of the shank piece S is caused to penetrate the entire thickness of the insole I and to become clinched against the heel plate with which the last L is usually provided. The tack inserted through the hole at the forward end of the shank piece also is driven through the entire thickness of the insole I and either is clinched against the metal bottom of the last, if such is provided, or against a metal insert member if especially provided for this purpose in the last bottom, or the tack is driven into the last, if its bottom is unarmored. In the latter case the tack is again pulled out of the last as a result of the last pulling operation and the end of the tack protruding into the shoe is then snipped off.

10 As illustrated in Figs. 3 and 4, the lower end of the throat 20 has a beaded portion 28 on which two tack holding jaws 30 are mounted for pivotal movement toward and from each other. The jaws are hollow and form, when closed against each other, a tack holding pocket. Their lower ends are conically shaped so that the jaws may 15 be used in properly positioning the shank piece by partly entering the tack hole in the shank piece after the latter has been laid in proper position upon the shoe bottom. Thus the tack hole in the steel shank is located in alinement with a tack t held within the jaws 30, when 20 closed against each other, and in alinement with the driver 26. To afford pivotal motion of the jaws 30 with relation to each other, that is into and out of engagement with each other, the jaws 25 are provided with upwardly extending portions 32 which are hook shaped in cross section and engage the beaded annular portion 28 of the throat 20. To maintain the hook shaped portions 32 in pivotal engagement with the beaded portion 28 and to cause the lower ends of the jaws 30 to be closed against each other in the normal 30 position of the machine parts, there is provided a coil spring 34 which is located in an annular depression on the outside of the jaws and completely surrounds the jaws the opposite ends of the

spring being joined. The spring 34, even though it tends to hold the jaws closed against each other, can yield during the tack driving operation to permit the jaws 30 to spread apart under the wedging action of the tack *t*, particularly the head of the tack. Moreover, there is provided a collar or ring 36 loosely surrounding the hook shaped portions 32 of the jaws to prevent these portions from slipping off the beaded portion of the throat 20. The ring 36 also prevents the spring 34, on separation of the jaws 30, from riding up on the jaws.

As the jaws are being separated, due to the wedging action of the driven tack *t*, they slip out of the tack hole in the shank piece *S* when the tack point enters the insole (see Fig. 3). As illustrated in Fig. 4, the jaws 30, although widely separated to clear the head of the tack *t*, still maintain a guiding action on the tack, thus ensuring an accurate insertion of the tack at a predetermined location of the work parts.

Having described my invention, what I claim as new and desire to secure by Letters Patent of the United States is:

1. A machine for inserting fastenings into a work piece at predetermined portions thereof having, in combination, a throat for guiding the fastenings, an annular beaded lip on the lower extremity of the throat, two jaws freely projecting from the throat and adapted to act as a gage to position the work piece in a predetermined relation to the throat, the jaws being hollowed to form between them a pocket for receiving and centralizing a fastening, upper hook shaped extensions on said jaws adapted to engage said beaded lip to support the jaws and to afford pivotal movements thereof toward and away from each other and with relation to the throat, and an annular spring member surrounding both jaws and adapted normally to hold the jaws closed against each other but arranged to yield to permit the jaws to separate upon the driving of a fastening so as to enable the fastening to pass therethrough with the jaws maintaining a centralizing action upon the fastening during the driving operation.

2. A machine for inserting a fastening through a hole in a steel shank piece into a shoe bottom member to attach the shank piece to the bottom member having, in combination, a tubular throat for guiding the fastening, an annular beaded lip on the lower extremity of the throat, two jaws freely projecting from the throat and provided with conically shaped extremities adapted partially to enter the hole in the shank piece to position the shank piece with relation to the throat with the hole in the shank piece in alignment with the throat, the jaws being hollowed to form between them a pocket for receiving and centralizing the fastening, upper hook shaped extensions on said jaws adapted to engage said beaded lip to support the jaws and to afford pivotal movements thereof toward and away from each other and with relation to the throat, and an annular spring member surrounding both jaws and adapted normally to hold the jaws closed against each other but arranged to yield to permit the jaws to separate upon the driving of the fastening and to move out of the hole in the shank piece while still maintaining a centralizing action upon the fastening until it is fully driven.

3. A machine for inserting fastenings into a work piece at predetermined portions thereof having, in combination, a throat for guiding the fastenings, an annular beaded lip on the lower

extremity of the throat, two jaws freely projecting from the throat and adapted to act as a gage to position the work piece in a predetermined relation to the throat, the jaws being hollowed to form between them a pocket for receiving and centralizing a fastening, upper hook shaped extensions on said jaws adapted to engage said beaded lip to support the jaws and to afford pivotal movements thereof toward and away from each other and with relation to the throat, an annular spring member surrounding both jaws and adapted normally to hold the jaws closed against each other but arranged to yield to permit the jaws to separate upon the driving of a fastening so as to enable the fastening to pass therethrough with the jaws maintaining a centralizing action upon the fastening during the driving operation, and means for holding said jaws with their hook shaped extensions at all times in pivotal engagement with said lip.

4. A machine for inserting fastenings into a work piece at predetermined portions thereof having, in combination, a throat for guiding the fastenings, an annular beaded lip on the lower extremity of the throat, two jaws freely projecting from the throat and adapted to act as a gage to position the work piece in a predetermined relation to the throat, the jaws being hollowed to form between them a pocket for receiving and centralizing a fastening, upper hook shaped extensions on said jaws adapted to engage said beaded lip to support the jaws and to afford pivotal movements thereof toward and away from each other and with relation to the throat, an annular spring member surrounding both jaws and adapted normally to hold the jaws closed against each other but arranged to yield to permit the jaws to separate upon the driving of a fastening so as to enable the fastening to pass therethrough with the jaws maintaining a centralizing action upon the fastening during the driving operation, and an annular member surrounding the hook shaped extensions of the jaws to prevent said extensions from becoming disengaged from said beaded lip.

5. A machine for inserting a fastening through a hole in a steel shank piece into a shoe bottom member to attach the shank piece to the bottom member having, in combination, a tubular throat for guiding the fastening, an annular beaded lip on the lower extremity of the throat, two jaws freely projecting from the throat and provided with conically shaped extremities adapted partially to enter the hole in the shank piece to position the shank piece with relation to the throat with the hole in the shank piece in alignment with the throat, the jaws being hollowed to form between them a pocket for receiving and centralizing the fastening, upper hook shaped extensions on said jaws adapted to engage said beaded lip to support the jaws and to afford pivotal movements thereof toward and away from each other and with relation to the throat, an annular spring member surrounding both jaws and adapted normally to hold the jaws closed against each other but arranged to yield to permit the jaws to separate upon the driving of the fastening and to move out of the hole in the shank piece while still maintaining a centralizing action upon the fastening until it is fully driven, and an annular member surrounding the hook shaped extensions of the jaws to prevent said extensions from becoming disengaged from said beaded lip.
